CLOSURE

Elbert M. Reeder, Port Arthur, Tex.

Application October 6, 1939, Serial No. 298,308

1 Claim. (Cl. 215—74)

This invention appertains to new and useful improvements in closures especially adapted for bottles or containers which are frequently used, such as bottles containing rubbing alcohol, bluing, face lotions, etc.

The principal object of the present invention is to provide a cap structure which includes a quick-acting closure which can be readily opened and which self closes itself, thus eliminating the necessity of removing the cap from the bottle.

Another important object of the invention is to provide a secondary closure for caps and the like which will be of simple construction and of low cost to manufacture.

These and other objects and advantages of the invention will become apparent to the reader of the following specification.

In the drawing:

Figure 1 is a top plan view of the cap applied to a bottle.

Fig. 2 is a side elevational view of the cap applied to a bottle.

Fig. 3 is a vertical sectional view through the closure and bottle showing the closure applied.

Fig. 4 is a top plan view of a modified form of the cap.

Fig. 5 is a top plan view of the modified form of cap showing the retaining lug in bent-up position.

Fig. 6 is a sectional view on line 6—6 of Fig. 4.

Referring to the drawing wherein like numerals designate like parts, it can be seen that numeral 5 represents a conventional bottle having a thread formed neck 6 to which the cap generally referred

to by numeral 7 is applied.

This cap consists of the top 8 and the thread formed skirt portion 9.

As is clearly shown in Fig. 3, this form of cap is usually provided with a liner 10, and this liner, as well as the cap is formed with registering openings 11, over which the closure flap 12 of the secondary closure generally referred to by numeral 13 is disposable, it being preferable that this closure flap carry a packing pad or the like 14 on its side opposed to the cap 8.

This secondary closure is constructed from a sheet of spring metal, the same being of elongated

construction and slotted as at 15—15 to define the narrow legs 16—16 which at their free ends are welded as at 17 to the top of the closure cap 8 so that the closure flap 12 will be disposed over the openings 11, while the finger tab end portion 18 ⁵ will project outwardly beyond the cap and this is preferably bent to an inclined position as shown in Fig. 3. Obviously by pushing inwardly on the tab 18, the closure flap 12 will be lifted so the liquid can be poured through the opening 11 when 10 the bottle is inverted.

A somewhat modified form of the invention is shown in Figs. 4, 5 and 6, wherein the cap is denoted by the reference character 7a, and the secondary closure by reference character 13a. In 15 this connection the closure flap is denoted by 12a, the legs by reference character 16a, and the tab by reference character 18a.

Instead of having the leg 16a welded to the cap as shown in Fig. 1, the cap is slotted so as to define 20 the bridge pieces 19 under which the leg portions are slipped and furthermore the top of the cap is constructed to provide the lugs 20 which are bent over the closure flap 12a when the merchandise is being shipped. When the consumer is ready to 25 use the contents of the bottle, these lugs 20 can be bent upwardly to the position shown in Fig. 5 and the closure 12a is now ready to be actuated.

While the foregoing specification sets forth the invention in specific terms, it is to be understood 30 that numerous changes in the shape, size and materials may be resorted to without departing from the spirit and scope of the invention as claimed hereinafter.

Having described the invention, what is claimed 35 as new is:

A closure for receptacle tops comprising an elongated strip of spring material slit to provide a pair of legs and a central portion at one end of said strip, the other end of the strip being bent 40 downwardly and in spaced relation to the receptacle top, said legs being positively secured to the top, said portion between the legs defining a closure for the top of the receptacle and adapted to be moved upwardly by pushing the downwardly 45 bent end portion of the strip inwardly.

ELBERT M. REEDER.
